UNITED STATES PATENT OFFICE.

EDWARD HAAS, OF BROOKLYN, NEW YORK, ASSIGNEE OF ONE-HALF TO MILFORD B. FERGUSON, OF BROOKLYN, NEW YORK.

WRAPPING MACHINE.

Application filed November 15, 1922. Serial No. 601,013.

To all whom it may concern:

Be it known that I, EDWARD HAAS, a citizen of the United States, residing at Brooklyn, in the county of Kings, in the State 5 of New York, have invented certain new and useful Improvements in Wrapping Machines, of which the following is a specification.

The invention relates to an improvement 10 in wrapping machines, and more particularly to an improvement in machines for wrapping irregularly shaped articles, such as lollipops.

It has been proposed heretofore to wrap 15 lollipops and the like by machine, but, so far as known, the machines heretofore produced for this purpose have not proven successful, with the result that lollipops are still wrapped by hand. The object of the 20 present invention is to improve upon the construction of wrapping machines of this type in order to wrap lollipops and similar articles much faster and better than the wrapping can be accomplished by hand. 25 For convenience of description and to illustrate the principles of the invention, the improved wrapping machine will be described as particularly adapted for wrapping lollipops. It will be understood, 30 however, that the invention is not to be restricted to this purpose, inasmuch as certain features of it are equally well adapted for use in wrapping other irregularly shaped articles.

35 A lollipop consists of a flattened, irregular, and more or less oval shaped lump of candy mounted on the end of a wooden stick which serves as a handle. By reason of this peculiarity of structure, considerable 40 difficulty has been experienced in feeding the lollipops to the wrapping machine so that they will be properly engaged by the fingers on the carrier or conveyor which advances them through the wrapper folding devices. One feature of the present 45 invention is the provision of means for receiving the lollipops from the feeding means, and for holding them in the path of travel of the carrier until they are properly engaged by the carrier fingers. The 50 means for receiving the lollipops from the feeding means and positioning them in the path of travel of the carrier fingers comprises gripping means which open to receive the stem of the lollipop, close upon

the stem to hold it in position to be engaged by the next succeeding carrier finger, and release it when the carrier finger is properly in engagement therewith. By providing this gripping means for centering 60 the lollipops in the path of travel of the carrier fingers, the lollipops can be fed through the machine and wrapped much faster and better than it has heretofore been possible to accomplish these operations. 65

Upon the completion of folding the wrapper about the candy portion of the lollipop, the free ends of the wrapper extend in the direction of the stick. These ends of the wrapper are then twisted about the stick 70 at the base of the candy so as to hold the wrapper in place. Another feature of the invention is the provision of improved means for twisting the ends of the wrapper about the stick. The twisting mechanism 75 comprises a plurality of pairs of clamping jaws which hold the lollipops by the candy portion and to which a rotative movement is imparted. Cooperating with each pair of clamping jaws is a pair of twisting fingers adapted to close upon the ends of the wrapper, and between which the twist is made by the rotating clamping jaws. The clamping jaws are adapted to receive the lollipops from the carrier fingers. For this purpose the clamping jaws 80 are mounted on a rotatable frame which revolves on a horizontal plane, and the carrier fingers are provided with lateral recesses so as to permit of the ready disengagement of the lollipop sticks. As one 85 pair of clamping jaws is moving into position to receive a lollipop from the carrier, the next preceding pair of clamping jaws is moving into position to discharge a completely wrapped lollipop from the machine. 90

The preferred form of the invention is illustrated in the accompanying drawings, in which Fig. 1 is a front side elevation of the improved wrapping machine; Fig. 2 is 100 a plan of the parts shown in Fig. 1; Fig. 3 is a rear end elevation of the wrapping machine; Fig. 4 is an elevation, on an enlarged scale, of a part of the front end of the machine; Fig. 5 is a rear elevation of the parts shown in Fig. 4; Fig. 6 is an enlarged detail of one of the carrier fingers; Figs. 7 and 8 are side and rear end elevations, respectively, of the device for making the preliminary fold in the wrapper; 105 110

Fig. 9 is a side elevation, partly in section, of the twisting mechanism; Fig. 10 is a detail of the parts for actuating the twisting fingers; Figs. 11 and 12 are a plan and side view, respectively, of the bottom plate of the wrapper folding devices; Figs. 13 and 14 are a plan and side elevation, respectively, of the upper plate of the wrapper folding devices; and Figs. 15 to 19, inclusive, illustrate various stages in the wrapper folding and twisting operations.

The improved lollipop wrapping machine, as illustrated in the drawings, comprises in common with other machines of this type, means for feeding the lollipops to be wrapped one at a time to the machine, means for conveying the lollipops and the wrappers through the wrapper folding devices by which the wrappers are folded on the candy part of the lollipops, and means for twisting the ends of the wrappers about the stick part of the lollipops so as to secure the wrappers in place. The present invention is concerned more particularly with the means for feeding the lollipops to the machine and positioning them in the path of travel of the carrier fingers by which they are conveyed through the wrapper folding devices, and with the means for twisting the wrappers about the stick at the base of the candy part of the lollipop.

The unwrapped lollipops 20 are fed one at a time to the machine by an endless conveyor composed of the chains 21 and 22 provided with the lugs 23. The lugs on the chain 21 engage the candy part or head of the lollipops, and the lugs on the chain 22 engage the handle part or sticks of the lollipops. For this reason the lugs on the two chains are arranged in staggered relation. The rear ends of the chains pass over the sprocket wheels 24 which are supported from the upright 25. The forward end of the conveyor chains pass over the driving sprocket 27 mounted on the shaft 28 journaled in the frame of the machine. On the outer end of the shaft 28 is mounted a sprocket wheel 30 which is driven from a second sprocket wheel 31 mounted on the cam shaft 32 journaled at one end in the frame of the machine and at the other end in the bracket 33. The outer end of the shaft 32 carries a bevel gear 34 which meshes with and is driven by a bevel gear 35 fixed at one end of a shaft 36 upon which is mounted a sprocket wheel 37 which supports the rear end of the carrier chain 38 by which the lollipops are conveyed or advanced through the wrapper folding devices.

The lollipops are received from the lugs 23 of the conveyor chains by the carrier fingers 40 which are mounted at uniform distances apart on the carrier chains 38. The construction of the carrier fingers is shown in detail in Fig. 6. The top end of

the fingers is recessed to receive the free end of the lollipop sticks. In order that the lollipops may be held firmly by the carrier fingers 40, a spring 41 is provided, the free end of which projects loosely into the recess. When the lollipops are fed to the machine, they are first received by the gripping means or centering fingers 42 and 43 (Figs. 4 and 5) and are held in the path of travel of the carrier fingers 40. The lollipops are discharged by the conveyor lugs onto the platform 44, and at the moment of discharge the centering fingers 42 and 43 occupy the positions indicated in dotted lines in Fig. 4. The centering fingers are then closed upon the stick of the lollipop and it is held firmly until engaged by the oncoming carrier finger 40. When the latter has advanced sufficiently to close the stick engaging recess therein over the lollipop stick, the centering fingers are moved outwardly to permit the carrier finger to convey the lollipop into the wrapper folding devices.

The centering finger 42 is secured to a pin 45 pivoted in the upper end of a bracket 46 secured to the machine frame. The centering fingers 43, which are adapted to straddle the single centering finger 42, are fixed on one end of a pin 47 pivoted in the bracket 48 secured to the machine frame. Secured to the pin 45, in fixed relation with the finger 42, is an arm 49 pivotally connected with the upper end of a link 51, the lower end of which is connected with a head 52 adapted to slide on a vertically arranged rod 53 secured at its upper end to the guide 54 upon which the upper part of the carrier chain 38 rests. Secured to the pivot pin 47, in fixed relation with the fingers 43, is an arm 55 pivotally connected with the upper end of a link 56 which is connected at its lower end with the head 52. The centering fingers 42 and 43 are opened by a cam 58 mounted on the cam shaft 32 and are yieldingly closed upon the lollipop sticks by a spring. The arm 59 of a bell-crank lever pivoted at 60 in the machine frame carries a cam roll 61 which travels on the periphery of the cam 58. The other arm 62 of the bell-crank is bifurcated at its outer end and loosely embraces the head 52. When the carrier finger has gripped the end of the lollipop stick, the centering fingers 42 and 43 are moved out of the path of travel of the carrier finger by means of the active part of the cam 58. The coil spring 64, acting to close the centering fingers upon the lollipop sticks, has its lower end bearing against check-nuts 65 threaded on the rod 53 and its upper end bearing against the underside of the head 52.

The actuation of the centering fingers 42 and 43 is so timed that the lollipops are received from the conveyor lugs and posi-

tioned in the path of the carrier fingers 40, and then opened to permit the passage of the carrier fingers, whether the carrier chain is driven intermittently or at a uniform rate 5 of speed. The forward end of the carrier chain 38 is supported on the driving sprocket 67 mounted on the shaft 68 journaled transversely of the machine. One end of the shaft 68 is provided with a sprocket 10. 69 which is driven from a sprocket 70 mounted on the jack-shaft 71, which is driven from the main shaft 72 by means of a chain 73. At one end of the shaft 72 is mounted a pulley 74 which may be driven 15 from any convenient source of power; and on the front end of the shaft 72 is mounted a hand-wheel 75. The carrier fingers 40 are arranged at uniform intervals on the carrier chain 38 and serve to transport the 20 lollipops and their wrappers through the wrapper folding devices, which are generally indicated at 77 (Fig. 1) and transfer the wrapped lollipops to the twisting mechanism which is generally indicated at 25 78 (Fig. 1).

When a carrier finger has moved into contact with the stick of the lollipop held by the centering fingers and continues its travel to carry the lollipop and a wrapper 30 into the wrapper folding devices, it first enters a former (as it is known) which, when the head or candy part of the lollipop has entered therein, is adapted to move with the lollipop for a short distance to make 35 the first crease in the wrapper in advance of the lollipop. The former 80 (Figs. 7 and 8) is a box like structure mounted to slide on the guide 81 secured to a cross-piece 82 which extends transversely of the 40 uprights 83 upon which the wrapper feed rolls are mounted. The former is open at 84 on its bottom side to permit the carrier fingers to pass therethrough. The front end of the former is provided with the converging springs 85 which serve to center 45 the head of the lollipop and also to make the first fold in the wrapper. The former is held stationary until the head of the lollipop has entered therein and then the 50 former is moved with the lollipop until the beginning of the first fold is made in the wrapper 79, as shown in Fig. 14. The former is actuated from a cam 87 mounted on the main shaft 72. The connections between the cam 87 and the former comprise 55 an arm 88 bifurcated at its forward end to loosely embrace the shaft 72. The arm 88 carries the cam roll 89 which is adapted to ride on the periphery of the cam 87. The rear end of the arm 88 is pivotally connected with an arm 90 of a bell-crank pivoted at 91. The other arm 92 of the bell-crank is connected with one end of a link 93, the other end of which is connected with the 60 former 80.

The wrapper is advanced into the path of travel of the lollipop and is severed in the usual manner. The roll of wrapping material 95 is supported on the upper end of the upright 96, and the wrapper is passed 70 under an idler roll 97 supported from an arm 98 and then down between the feed rolls 99 and 100. The feed rolls are driven intermittently from a crank 101 fixed on the outer end of the shaft 68 and which is connected by the link 102 with the crank 103 secured to the outer end of the shaft 104. On the shaft 104 is mounted the sprocket 105 which drives the sprocket 106 by means of the chain 107. The sprocket 106 is 80 mounted on one end of the shaft 108 which supports the feed roll 99 and on the other end of which is mounted the gear 110. The gear 110 meshes with and drives the gear 111 which is mounted on one end of the 85 shaft 112 upon which the feed rolls 100 are mounted. When the feed rolls have been actuated to advance the wrapper into the path of travel of the lollipop and the former, the requisite length is severed by 90 the shears. The fixed blade of the shears is indicated at 114 and the movable blade at 115. The movable blade is mounted on the upper end of a vertically arranged rod 116. The lower end of the rod 116 projects 95 below the machine frame and is provided with an arm 117 pivotally connected with one end of an arm 118, the forward end of which is bifurcated and loosely straddles the shaft 72. The arm 118 carries the cam roll 100 119 and is adapted to ride on the cam 120 mounted on the shaft 72.

The wrapper folding devices, comprise a lower plate 122 supported from the machine frame and an upper plate 123 removably supported on the lower plate. The lower plate is provided with the pins 124 which are adapted to be received in the holes 125 in the upper plate 123. The upper plate is provided with the channel pieces 126 and 127 which are adjustable laterally to accommodate different widths of candy. The sides 128 of the channel pieces 127 converge from the point of entrance to the point 129 and the sides 130 of the channel pieces 126 110 115 form a straight channel. The function of the channels formed by the pieces 126 and 127 is to turn the side edges of the wrapper downwardly so that they may be folded up against the bottom of the head of the lollipop by the lower plate 122. Figs. 16 and 17 illustrate the action of the sides 128 of the channel pieces 127 on the side edges 131 of the wrapper.

The lower plate 122 is provided throughout its length with a longitudinal slot 133 which is adapted to accommodate the crease 134 formed in the wrapper as the lollipop enters between the plates. The forward end of the lower plate is provided with the 130

channel pieces 135 which make the creases 136 in the wrapper at the lateral edges at the head of the lollipop, as shown in Fig. 16. The flaring edges 131 turned down by 5 the channel pieces of the upper plate enter the converging slots 137 in the lower plate. As the lollipop advances through the space between the plates, the side 138 of the wrapper encounters the edge 139 of the 10 lower plate and is thereby folded against the bottom side of the head of the lollipop, as shown in Fig. 18. The further advance of the lollipop through the machine brings the side 140 in contact with the edge 141 15 of the lower plate, and the side 140 is then folded down over the side 138. The carrier fingers 40 pass through the slot 133, and in order to prevent the downturned side extensions of the wrapper from entering the 20 slot 133 at the points 144 and 145, spring-pressed blocks 146 and 147 are provided. When the carrier fingers come in contact with the pieces 146 and 147, the latter move back out of the way, and when the carrier 25 fingers have passed beyond them, they return into position again to close the gaps made in the edges 139 and 141 by the slot 133.

When the lollipops emerge from between 30 the wrapper folding plates, they are projected by the carrier fingers into the wrapper twisting mechanism. The wrapper folding devices serve to fold the wrapper about the sides and the front and side edges of 35 the head of the lollipop, leaving the rear ends of the wrapper extending along the stick. The wrapper twisting mechanism serves to twist the rear ends of the wrapper about the stick at the base of the head of the 40 lollipop. The wrapper twisting mechanism 78 is located at the end of the wrapper folding devices and comprises two pairs of oppositely arranged clamping devices 150 and 151 which are adapted to receive and hold 45 the lollipops by the wrapped candy portion during the twisting operation. When a carrier finger emerges from between the wrapper folding plates with a lollipop, it pushes the lollipop into position to be received by the clamping device then opposite the wrapper folding plates. Immediately 50 the clamping device has closed upon the candy portion of the lollipop it is swung on a horizontal plane, and this movement 55 serves to detach the lollipop stick from the carrier finger. In this connection, it will be noted that the stick holding recess in the upper end of each carrier finger is open at the sides so as to permit the ready disengagement of the stick from the holding 60 spring 41.

The clamping devices of the twisting mechanism are of a duplicate construction and therefore it will only be necessary to describe in detail the construction and mode

of operation of one of them. The clamping device 151 comprises a pair of shovel-shaped clamping jaws 153 supported on the outer ends of a pair of arms 154 adjustably secured in the knuckles 155 pivotally mounted on a head 157 journaled in the rotatable frame 158. The inwardly projecting arms 156 of the knuckles 155 are articulated by a pin and slot connection 159 so that the clamping jaws may be moved in unison, 70 but in opposite directions. The clamping jaws are moved toward each other to close upon the lollipop by means of a spring 160 interposed between the arms 156 and a spring housing 161 secured to the head 157. 75 When the twisting operation is completed, the clamping jaws 153 are moved apart to release the lollipop and for this purpose a pin 162 is provided slidably mounted in the hub 163 of the head 157. The pin 162 is pushed against the knuckles 155 to open the clamping jaws 153 by means of the wedge-shaped end 165 of a vertically arranged rod 166 slidably mounted in the upper part of the frame 158 and guided at 80 its upper end in the bracket 167 (Fig. 3) secured to the frame of the machine. The rod 166 is pushed downwardly to open the clamping jaws 153 by means of a bell-crank 168 mounted on the bracket 167. The arm 169 of the bell-crank 168 engages a collar 170 secured to the upper end of the rod 166 and the other arm 171 of the bell-crank is pivotally connected by a link 172 with the upper end of the lever 173 pivoted at 174. The lower end of the lever 173 is connected with an arm 175, the free end of which is slotted to straddle the shaft 176 and carries a cam roll 177 which rides on the periphery of a cam 178 fixed on the shaft 176. The shaft 176 is journaled in the machine frame and at one end carries a bevel gear 179 which meshes with and is driven by a second bevel gear 180 mounted on the transverse shaft 68. 11

The twisting operation is performed while the clamping device holding the lollipop traverses a semi-circle. During this movement the ends of the wrapper are held against the stick of the lollipop by a pair 11 of twisting fingers 182 and 183 which are opened to permit the positioning of the lollipop between the clamping jaws and which close again immediately thereafter. The two pairs of twisting fingers 182 and 183 are supported on the outer ends of the rods 184 and 185 journaled in the outer ends of the bracket 186 secured to the top of the frame 158. The lower ends of the twisting fingers are hook-shaped, as shown in Fig. 3, 12 and are oppositely disposed so as to enclose the ends of the wrapper between them and thereby effect the twisting of the wrapper about the stick. The rods 184 and 185 are rotated in opposite directions to open the 13

twisting fingers and a reverse movement is imparted to the rods to close the twisting fingers upon the ends of the wrapper. For this purpose the rods are provided with intermeshing gears 187 and 188 (Fig. 10), respectively. The gear 187 meshes with and is rotated by a vertically arranged rack 189 depending from a collar 190 slidingly mounted on the rod 166. The collar 190 and the rack 189 are vertically reciprocated to rotate the rods 184 and 185 to thereby open and close the twisting fingers by means of a bell-crank 192 pivoted in the bracket 167. One arm 193 of the bell-crank 192 engages the collar 190 and the other arm 194 of the bell-crank is connected by a link 195 with the upper end of a lever 196 mounted on the pivot 174. The lower end of the lever 196 is connected with an arm 197, the outer end of which carries a roll 198 in engagement with the periphery of a cam 199 mounted on the shaft 176. The construction and arrangement of these parts are the same as the construction and arrangement of the corresponding parts in engagement with the cam 178 and lie back of the latter parts viewed from the left end of the machine, as seen in Fig. 3.

In order that the ends of the wrapper may be twisted about the stick by the twisting fingers 182 and 183, the clamping jaws 153 are rotated. For this purpose the end of the hub 163 of the head 157 is provided with a bevel gear 202 which meshes with and is driven by a bevel gear 203 mounted on the upper end of a shaft 204 vertically arranged in the hub 223 of the frame 158. The lower end of the shaft 204 projects downwardly through the table part of the machine and carries a pinion 205 which is driven by a gear 206 mounted on a shaft 207 journaled in the machine frame. To the lower end of the shaft 207 is secured a bevel gear 208 which is driven by a bevel gear 209 mounted on the inner end of a shaft 210 journaled in the machine frame. The outer end of the shaft 210 carries the slotted disc 211 of a Geneva gear construction. The roll 212 adapted to enter the slots 213 in the disc 211 and thereby impart an intermittent movement to the parts connected with the disc is carried by a gear 214 mounted on a stud 215 fixed in a bracket 216. The gear 214 is driven from a gear 218 fixed on the front end of the shaft 68 through an intermediate gear 219 mounted on the stud 220 fixed in the bracket 216.

The clamping jaws are rotated to cause the twist to be made in the wrapper by the twisting fingers while the lollipop is being transported from the point where it is received from the wrapper folding devices to the point where it is discharged from the machine. The frame 158 which supports the parts of the twisting mechanism is ro-

tated to transport the lollipops from the point where the clamping jaws receive the lollipops from the wrapper folding devices to the point of discharge from the machine. The frame 158 rests on and is secured to a gear 222. The gear 222 meshes with and is driven by the gear 224 fixed on the upper end of the shaft 207. The gears which rotate the frame 158 and the clamping jaws are so proportioned that, while the frame 158 travels a semi-circle in passing from the point where the lollipops are received from the wrapper folding devices to the point where they are discharged from the machine, the clamping jaws make three revolutions, which are sufficient to cause the twisting fingers to securely twist the ends of the wrapper about the stick of the lollipop, as shown in Fig. 19.

As one pair of clamping jaws approaches the point to receive the lollipop from the wrapper folding devices, and the other pair of clamping jaws approaches the point of discharge, the rod 166 is moved downwardly to open the clamping jaws, and at the same time the twisting fingers begin to open. Both pairs of clamping jaws and twisting fingers are fully opened when the frame 158 momentarily comes to rest with the jaws and fingers in alinement with the carrier fingers 40. During this pause the lollipop, which has just passed through the wrapper folding devices, is inserted between the alined clamping jaws by the carrier fingers holding the lollipop, and immediately thereafter the clamping jaws close upon the lollipop, the twisting fingers close upon the ends of the wrapper and the frame 158 is swung laterally to disengage the lollipop from the carrier finger. It will be incidentally observed that after the clamping jaws have discharged the lollipop from the machine, they close again while passing from the point of discharge from the machine to the point where the next lollipop is received from the wrapper folding devices.

The mode of operation of the improved wrapping machine has been described in connection with the description of the construction of the various parts of the machine. Briefly, the feed conveyor 19 serves to bring the lollipops within the range of the centering fingers 42 and 43 which hold the lollipops in the path of travel of the carrier fingers 40 so that the latter will properly grasp the end of the lollipop sticks. The lollipop then enters the former 80 which moves with the lollipop until the beginning of the first fold is made in the wrapper, after which the former returns to its normal position and the lollipop continues its travel through the wrapper folding devices by which the top and bottom sides of the wrapper are first folded down against the lollipop and then the side edges 130

are folded under, one upon the other. The lollipops emerge from the wrapper folding devices with the rear ends of the wrapper extending along the sticks. The lollipops are then received by the clamping jaws of the twisting mechanism and the twisting fingers close upon the ends of the wrapper so that, as the clamping jaws are rotated while the lollipop is being transported to 10 the point of discharge from the machine, the ends of the wrapper are firmly twisted about the stick at the base of the candy part of the lollipop.

It will be understood that the invention 15 is not to be limited to the construction herein specifically illustrated, but that it may be embodied in other forms without departing from the spirit and scope of the following claims. Moreover, it is not limited 20 to wrapping lollipops but may be used for wrapping other articles, and especially those of irregular shape.

Having thus described the invention what I claim as new is:—

25 1. A machine for wrapping lollipops having in combination wrapper folding devices, means for conveying the lollipops through the wrapper folding devices, means for feeding the lollipops one at a time to the machine, gripping means, and means for actuating the gripping means to cause it to receive the lollipops from the feeding means and hold them in the path of travel of the conveying means and release them 30 when they have been engaged by conveying means.

2. A machine for wrapping lollipops having in combination wrapper folding devices, means for conveying the lollipops through the wrapper folding devices, said conveying means comprising fingers having recesses for engaging the ends of the lollipop sticks, means for feeding the lollipops one at a time to the machine, gripping means, and means for actuating the gripping means to cause it to receive the lollipops from the feeding means and hold them so that the ends of the lollipop sticks are received in the recesses of the fingers and 45 then release the lollipops.

3. A machine for wrapping lollipops having in combination wrapper folding devices, means for conveying the lollipops through the wrapper folding devices, means for feeding the lollipops one at a time to the machine, centering fingers for receiving the lollipops from the feeding means, and holding them until they are engaged by the conveying means, and means for actuating the fingers to close upon the lollipop sticks and to release them when they have been engaged by the conveying means.

4. A machine for wrapping lollipops having in combination wrapper folding devices, means for conveying the lollipops

through the wrapper folding devices comprising a series of carrier fingers having recesses for engaging the ends of the lollipop sticks, means for feeding the lollipops one at a time to the machine, pivotally mounted centering fingers for receiving the lollipops from the receiving means and holding them until they are engaged by the carrier fingers, and means for actuating the centering fingers. 75

5. A machine for wrapping lollipops having in combination wrapper folding devices, means for conveying the lollipops through the wrapper folding devices, said conveying means comprising a series of carrier fingers adapted to engage the ends of the lollipop sticks, means for feeding the lollipops one at a time to the machine, pivotally mounted centering fingers adapted to receive the lollipops from the receiving means and hold them in the path of travel of the carrier fingers, and cam actuated means for opening and closing the centering fingers. 80

6. A machine for wrapping lollipops having in combination wrapper folding devices, means for advancing the lollipops through the wrapper folding devices comprising a series of carrier fingers adapted to engage the ends of the lollipop sticks, means for feeding the lollipops to the machine, a pair of centering fingers adapted to receive the lollipops from the feeding means and hold them in position to be engaged by the carrier fingers, said centering fingers being 95 mounted to straddle the path of travel of the carrier fingers, and means for actuating the centering fingers to close upon the lollipop sticks to hold them in the path of travel of the carrier fingers and to open to permit the carrier fingers to advance. 100

7. A machine for wrapping lollipops having in combination wrapper folding devices, means for conveying the lollipops through the wrapper folding devices, means for feeding the lollipops to the machine, means for positioning the lollipops in the path of travel of the conveying means, means for feeding the wrappers into position to be engaged by the lollipops, and a twisting mechanism adapted to disengage the wrapped lollipops from the conveying means and twist the loose ends of the wrapper about the lollipop sticks. 110

8. A machine for wrapping lollipops having in combination wrapper folding devices, conveying means for advancing the lollipops through the wrapper folding devices comprising carrier fingers provided with spring means having lateral openings to hold the ends of the lollipop sticks, means for positioning the lollipops in the path of travel of the carrier fingers, means for feeding the wrappers into position to be engaged by the lollipops, and a twisting mechanism 125

comprising a pair of clamping jaws to receive the wrapped lollipops, a pair of twisting fingers to engage the loose ends of the wrappers, means for rotating the clamping jaws, and means for rotating the twisting mechanism as a whole to disengage the lollipops from the carrier fingers.

9. A machine for wrapping lollipops having in combination wrapper folding devices, means for conveying the lollipops through the wrapper folding devices comprising carrier fingers provided with recesses for engaging the ends of the lollipop sticks, means for feeding the lollipops to the machine to be engaged by the carrier fingers, means for feeding the wrappers into position to be engaged by the lollipops, a twisting mechanism for twisting the loose ends of the wrappers about the lollipop sticks, and means for actuating the twisting mechanism to disengage the lollipops from the carrier fingers.

10. A machine for wrapping lollipops having in combination wrapper folding devices, means for conveying the lollipops through the wrapper folding devices, means for feeding the lollipops to the machine, means for feeding the wrappers into the path of travel of the lollipops, and a twisting mechanism for twisting the loose ends of the wrappers about the lollipop sticks adapted to receive the lollipops from the conveying means, and means for actuating the twisting mechanism to disengage the lollipops from the conveying means.

11. A machine for wrapping lollipops having in combination wrapper folding devices, means for conveying the lollipops through the wrapper folding devices, means for supplying the lollipops to the machine, means for feeding the wrappers into the path of travel of the lollipops and a twisting mechanism comprising a pair of clamping jaws for holding the wrapped head of a lollipop, a pair of fingers for engaging the loose ends of the wrapper at the base of the head of the lollipop, means for rotating the clamping jaws to thereby twist the loose ends of the wrapper about the stick, and means for moving the twisting mechanism to disengage the lollipop from the conveying means.

12. A machine for wrapping lollipops having in combination wrapper folding devices, means for conveying the lollipops through the wrapper folding devices, means for supplying the lollipops to the machine, means for feeding the lollipops into the path of travel of the conveying means, and a twisting mechanism comprising a pair of clamping jaws to receive the wrapped head of a lollipop from the conveying means, a pair of fingers for engaging the loose ends of the wrapper, and means for rotating the clamping jaws to thereby effect the twisting of

the loose ends of the wrapper about the stick of the lollipop.

13. A machine for wrapping lollipops having in combination, means for folding a wrapper about the lollipop so that the ends 70 of the wrapper will extend about the stick of the lollipop, means for clamping the wrapped head of the lollipop, means for grasping the loose ends of the wrapper and holding them against the stick, and means 75 for rotating the clamping means so that the loose ends of the wrapper will be twisted about the stick at the base of the head.

14. A machine for wrapping lollipops having in combination, conveying means 80 comprising a finger having means for holding the lollipop by the end of the stick, means for folding a wrapper about the head of the lollipop so that the loose ends of the wrapper will lie about the stick, a pair of 85 clamping jaws for receiving the wrapped head of the lollipop, means for engaging the loose ends of the wrapper, and means for rotating the clamping jaws to cause the ends of the wrapper to be twisted about the 90 stick.

15. A machine for wrapping lollipops having in combination, means for folding a wrapper about the head of the lollipop, conveying means having provision for 95 grasping the lollipop by the stick and advancing it through the folding means, clamping means for receiving the lollipop by the head from the conveying means, means for rotating the clamping means, and 100 means cooperating with the clamping means for twisting loose ends of the wrapper about the stick.

16. A wrapping machine having in combination a twisting mechanism comprising 105 a pair of oppositely disposed clamping means, each clamping means consisting of a pair of clamping jaws, means for actuating the jaws to hold the article during the twisting operation and to release the article 110 thereafter, a pair of fingers associated with each pair of clamping jaws to engage the ends of the wrapper, means for rotating the clamping jaws to thereby effect the twisting of the wrapper by means of the clamping 115 fingers, means for feeding an article and wrapper into position to be received by the clamping jaws, and means for moving the twisting mechanism to bring one pair of clamping jaws into position to receive the 120 next article and wrapper while the other pair of clamping jaws is discharging the wrapped article.

17. A wrapping machine having in combination a twisting mechanism comprising a 125 rotatable frame, two pairs of oppositely disposed clamping jaws mounted in the frame, means for actuating the jaws to close upon and release the article to be wrapped, a pair of twisting fingers associated with 130

each pair of clamping jaws for engaging the ends of the wrapper during the twisting operation, means for actuating the twisting fingers, means for rotating the clamping jaws to thereby effect the twisting of the wrapper about the article, means for advancing an article and wrapper into position to be engaged by the clamping jaws, and means for rotating the twisting mechanism when one pair of clamping jaws has received an article and wrapper to bring the other pair of clamping jaws into position to receive the next article and wrapper.

18. A wrapping machine for wrapping lollipops having in combination wrapper folding devices, conveying means for advancing the lollipops through the wrapper fold-devices comprising a series of carrier fingers provided with spring means and open-sided recesses for engaging the ends of the lollipops sticks, means for feeding the lollipops one at a time to the machine,

means for receiving and holding the lollipops until they are engaged by the carrier fingers, means for feeding the wrappers in the path of travel of the lollipops, and a twisting mechanism comprising a rotatable frame, two pairs of oppositely disposed clamping jaws mounted on the frame, means for opening the clamping jaws to receive the wrapped head of a lollipop from the conveying means and to discharge the wrapped lollipop from the machine, means for closing the clamping jaws to hold the lollipop during the twisting operation, a pair of twisting fingers associated with each pair of clamping jaws to engage the ends of the wrapper during the twisting operation, means for rotating the clamping jaws, and means for rotating the twisting mechanism to disengage the lollipops from the carrier fingers.

EDWARD HAAS.
